UNITED STATES PATENT OFFICE.

HENRI FONTY, OF PARIS, FRANCE, ASSIGNOR TO SOCIETE ANONYME DES ETABLISSEMENTS LEFLAIVE AND JEAN JACQUES KNECHT, OF PARIS, FRANCE.

CARRIER-DRIVE HEAD FOR LACE-BRAIDING MACHINES.

Application filed November 9, 1925. Serial No. 67,955.

To all whom it may concern:

Be it known that I, HENRI FONTY, a citizen of the French Republic, residing at Paris, Department of the Seine, in France, have 5 invented certain new and useful Improvements in Carrier-Drive Heads for Lace-Braiding Machines, of which the following is a specification.

The present invention relates generally to 10 lace braiding machines and more particularly to a new method of attaching the driver and the centre disc to their respective axes, the said members constituting what is called a braiding quoit or driver in lace 15 braiding machines. The centre disc for guiding and controlling the braiding-carrier is attached in such a manner on its fixed axis that it permits of the free passage of the foot of the braiding-carrier so that the periphery of the said foot may be tangential to 20 the axis of the head.

Consequently, it will be possible to employ 25 braiding-carriers having much wider foot or base portions so that such portions of two adjacent carriers may touch each other; or on the other hand the present size of the feet of the bobbin-carriers may be retained, the distance between the axes of two adjacent heads may be considerably decreased 30 for instance, a distance substantially equal to the diameter of the foot of the carrier.

The resulting advantages are numerous. For example, with the actual space occupied 35 by a machine it will be easy to add a greater number of carriers. The path of a carrier is shorter, and consequently there is less wear and more certain working for the withdrawals of the thread; there will be an increase in the number of revolutions of the 40 whole machine, and therefore a greater output.

The cap of the carrier may be larger and higher and it will hold a greater length of thread.

45 The accompanying drawing shows by way of example one construction according to the invention.

Fig. 1 is a vertical section through a number of braiding quoits with their respective 50 carriers, and the Fig. 2 is a plan view thereof, partly in section.

Referring now, more particularly, to the drawing, 1 designates the lower plate and 55 2 the upper plate of the machine. These in combination with the centre discs 3 and

3' respectively constitute the race-way for the braiding-carriers 4. The vertical spindles 5 and 5' are attached to the lower plate 1, and these spindles together with the pinions 6, sleeves 7 and drivers 8 provide the 60 means for driving the braiding carriers. The driver 8 and the centre disc 3 are in one piece. This piece is provided with an elongated lower portion of square cross section upon which the sleeve 7 slides freely 65 up and down according to the movements of a jacquard mechanism. The sleeve 7 is provided with two teeth 7' and with a central groove 7², in which there engages a control fork, not shown in the drawing. When the 70 fork is moved down, the teeth 7' of the sleeve 7, mesh with the teeth 6' of the driving pinion 6, transmitting the rotary motion of the pinion to the driver 8, that is to say, to the centre discs 3 (see second head Fig. 2). 75

In consequence of this action there is a crossing of the threads of the two carriers placed on the heads.

In effecting the foregoing advantages the 80 bolt or screw-head usually placed in the race-way plate 2 is according to the invention sunk in the driver and therefore shifted to a position below the upper plate 2.

With this object the driver 8 is provided 85 with a recess 9 in which the nut 10 is located and being below the plate 2 does not in any manner interfere with the feet of the carrier but permits of two adjacent carriers being arranged much closer together. The two arms 11 which connect the driver 8 with the 90 centre disc are cut away for two reasons:

1st to permit of the insertion and fastening of the nut.

2nd to allow the arms to act as a driver by 95 acting upon the lower disc 12 of the foot of the carrier and to serve also as a support for the foot of an adjacent carrier.

These arms may extend beyond the centre disc 3 above the race-way plate (Figs. 1 and 2) and operate in the same direction as the 100 lower arms 11.

Owing to this arrangement it is possible to drive the foot of the carriers at three independent places, namely at the lower disc 12, the upper disc 14 and the pin 15. The 105 drive will always be effected centrally and without jamming.

The base of the carrier is the largest 110 which can be made; it consists of the disc 14. Each disc may be of such size that two ad-

adjacent discs can touch each other or slightly spaced so that they allow sufficient play for the passage of a central unbraided thread when such is used.

5 It will be then possible to use larger and heavier crops containing more thread, without it being necessary to increase the space between the heads.

It is evident that by arranging the heads 10 close together, great advantages will be attained in the construction of machines.

Fig. 1, in which is shown a cop B² (dotted) of the usual form which may be used as a modification and a cop B' (full lines) which is preferably used with the construction according to the invention. It is also possible to employ a bolt 5' with a base which bears on a socket 17 and thereby ensures of the steadiness thereof.

20 Having thus fully described the invention what is claimed as new and desired to be secured by Letters Patent is:

1. A lace braiding machine including in combination, upper and lower plates the upper of which is provided with a circular 25 raceway, a series of discs arranged in the raceway and dividing the same into slots, braiding carriers mounted to slide in said slots, and drivers carrying the discs and arranged between the plates and including 30 spindles each driver being provided with a recess positioned beneath the upper plate, and fastening means for the spindles arranged within the recess.

2. A lace braiding machine as claimed in claim 1; wherein spaced arms are provided between the drivers and disc and constitute the connection therebetween and also provide the recess so that the fastening means may be inserted from the side; said arms also 40 serving as supports for adjacent carriers.

In testimony whereof I hereunto affix my signature.

HENRI FONTY.
